United States Patent

Des. 235,582
Patented June 24, 1975

235,582

CASE FOR REFRIGERATION TEST INSTRUMENTS OR THE LIKE

Raymond M. Beck, Los Angeles, Calif., assignor to
Mechanical Refrigeration Enterprises, North Holly-
wood, Calif.

Filed June 1, 1973, Ser. No. 366,172

Term of patent 14 years

Int. Cl. D3—02

U.S. Cl. D87—1 R

FIG. 1 is a front, top and right side perspective view of a case for refrigeration test instruments or the like showing my new design;

FIG. 2 is a rear, top and left side perspective view;

FIG. 3 is a front elevational view;

FIG. 4 is a rear elevational view;

FIG. 5 is a left side elevational view;

FIG. 6 is a top plan view; and

FIG. 7 is a bottom plan view.

I claim:

The ornamental design for a case for refrigeration test instruments or the like, substantially as shown.
